(57) **CLAIM**

The ornamental design for an impeller for pump, as shown and described.

DESCRIPTION

1. Impeller for pump

1.1 : Perspective

1.2 : Front

1.3 : Back

1.4 : Left

1.5 : Right

1.6 : Top

1.7 : Bottom

1.8 : Perspective view from the bottom

1.9 : Perspective view from the bottom

1.10 : Perspective view from the bottom

This design relates to an impeller for pump that can be used in combination with a drain motor used in a drain pump; fig. 1.1 is a perspective view of an impeller for pump showing our new design; fig. 1.2 is a front view thereof; fig. 1.3 is a back view thereof; fig. 1.4 is a left view thereof; fig. 1.5 is a right view thereof; fig. 1.6 is a top view thereof; fig. 1.7 is a bottom view thereof; and fig. 1.8, 1.9, 1.10 are perspective views from the bottom thereof.
